CLAY GUN PISTON POSITION INDICATING MEANS

Filed Sept. 24, 1931

INVENTOR
August F. Giese, Jr.

CHARLES MARSHALL ATTYS.

UNITED STATES PATENT OFFICE

AUGUST F. GIESE, JR., OF GARY, INDIANA

CLAY GUN PISTON POSITION INDICATING MEANS

Application filed September 24, 1931. Serial No. 564,788.

This invention relates to clay guns and concerns particularly a simple arrangement whereby the position of the piston within the cylinder and thereby the clay contents of the cylinder may be determined at any time at the gun or at a point remote therefrom.

In the operation of clay guns, it is quite important to know at all times the quantity of clay available in the cylinder and also to 10 gage the quantity of clay ejected from the cylinder for the proper plugging of a furnace tapping hole. It is also important to check the movement of the piston so that it will not strike or engage with pressure against the 15 end of the cylinder and thereby unnecessarily strain or injure the piston driving mechanism. In accordance with my invention, I provide means for indicating at the exterior 20 of the gun the location of the piston within the cylinder and I may accomplish this in a simple manner by means of a pointer supported to follow the reciprocating movement of the piston to indicate on a scale calibrated to represent the path of the piston.

25 Where it is desired to determine, at a point remote from the gun, the position of the piston therein, electrically operated indicating devices such as lamps may be utilized and the circuit therefor controlled by switch mechanisms operated by the movement of the gun piston.

My improved indicating arrangement is incorporated in the structure disclosed on the drawing, in which drawing

35 Figure 1 is a vertical diametral section of a clay gun showing the indicating arrangement applied thereto; and

40 Figure 2 is an enlarged view of the screw end of the gun to more clearly show the indicating arrangement.

The gun shown is of the type disclosed in my co-pending application Serial No. 562,034, filed September 10, 1931, in which a drive screw for the piston is held against rotational movement and is shifted axially by the rotation of a nut having threaded engagement therewith. Briefly, the gun structure shown comprises the cylinder 10 having the discharge nozzle 11 at one end and a head structure 12 at its other end. A piston 13 is re-

ciprocable in the cylinder and has rigidly secured thereto the screw 14 which extends outwardly through the head 12. The head structure forms an enclosure for the driving elements for the screw. These driving elements 55 comprise a nut 15 having screw threaded engagement with the screw and journalled in the head 12 by ball bearing structures 16 and 17. The piston and screw are held against rotational movement relative to the cylinder 60 as by means of side channels X in the cylinder and lugs Y extending from the sides of the piston. Between the bearing structures the nut has the flange 18 to which is secured the worm gear 19. The extension 12' on the head 12 encloses the worm 20 on the shaft 21 journalled in the sides of the extensions 12'. On a platform 22 extending from the head 12 is mounted an electric motor 23 connected 70 by a driving train 24 with the worm shaft 21 so that as the motor operates the nut 15 will be rotated to cause slow and powerful axial movement of the screw 14 to shift the piston in the cylinder for the ejection of clay 75 therefrom through the nozzle 11. For charging clay into the cylinder, outer and inner holes 25 and 26 are provided and adapted to be closed by cover structures 27.

A limit switch 28 driven by the motor through a transmission train 29 may be provided for controlling the motor circuit to stop the motor and thereby the piston when the piston reaches the ends of its stroke so as to prevent pressure contact of the piston with the cylinder ends. However, it is desirable and important to know at any time 80 the intermediate positions of the piston, as, from the position of the piston in the cylinder, the amount of clay discharged from or still remaining in the cylinder may be accurately determined. For example, if the cylinder when filled contains a certain volume of clay, and it is desired to project a certain volume of clay for the proper plugging 85 of a tapping hole, the piston when moved a certain distance will cause discharge of the required volume. By knowing from the exterior of the gun the exact location of the piston therein the movement of the piston 90

may be accurately regulated for the proper discharge of clay from the gun.

As in the gun structure shown the screw 14 does not rotate but moves only axially, 5 a simple position location indicating means would be a pointer 30 secured to the outer end of the screw and a scale 31 in the path of the pointer with the scale calibrated to indicate the path of the piston. Where the outer end 10 of the screw is protected by a stationary housing 32, the scale 31 could be supported from this housing and the housing provided with a slot 33 through which the pointer extends. The scale could be calibrated to indicate the 15 quarter, half, three-quarter, and end positions of the piston, or could be calibrated for any desired positions of the piston, so that when the pointer passes along the scale as the piston is reciprocated, it will indicate on the 20 scale the exact location at any time of the piston.

Instead of the pointer and scale, or in addition thereto, electrically controlled indicating means may be provided such as lamps 25 L, and these lamps could be located on the gun structure or at some point remote therefrom. In the arrangement shown, I have mounted a row of contact strips on the scale 31 to be engaged by a contact 34 on the pointer 30. I have shown end contacts C and C' and 30 four intermediate contacts C1, C2, C3, and C4. These contact strips are insulated from the dial and are insulated from each other by intervening insulation 35. The dial could 35 of course be of insulating material and the contact strips separated by air gaps. The end contact strips C and C' are comparatively short and correspond to the inner and outer positions of the piston in the gun cylinder. 40 The intermediate contacts C1, C2, C3, and C4 correspond with the travel of the piston through the four quarters of its stroke. It is understood of course that different subdivisions could be provided. 45 In the arrangement shown, the lamps L and L⁵ are connected from one terminal thereof with the end contact strips C and C' respectively, while the lamps L¹, L², L³ and L⁴ are connected with the contact strips C1, C2, 50 C3 and C4 respectively. The other terminals of all of the lamps are connected with a current supply conductor 36 connected with a current supply source such as a battery B, or the same source which supplies the motor 55 23. The other terminal of the battery is connected through a suitable switch 37 with the framework of the gun as for example the screw housing 32, and the contact 34 on the pointer 30 is connected through the pointer 60 with the screw and consequently the gun framework. Upon closure of the switch 37, the electrical indicating system will function. When the piston is at the inner end of the cylinder, the contact 34 will be in engagement with the end contact strip C and the

lamp L will be illuminated to indicate such position of the piston. The contact 34 may be of a length greater than the insulation width between the contact strips and then as 70 the piston moves outwardly and the contact 34 engages the contact strip C1, both the lamps L and L¹ will be momentarily illuminated to indicate to the operator that the piston is starting its travel along the first 75 quarter of its path. When the contact engages only with the strip C', only lamp L¹ will be illuminated until the contact reaches over to the contact strip C2 when both lamps L¹ and L² will be illustrated to indicate that the piston is starting on the second quarter of 80 its travel. The entrance into and travel of the piston over its respective quarter is thus indicated by the lamp and when the contact 34 finally reaches the end contact C', the lamp L⁵ will illuminate to indicate that the strip has reached the outer end of its path. The outer end of the pointer 30 will accurately indicate on the scale the travel and 85 positions of the piston within the cylinder. The lamps may be properly mounted directly 90 on the gun structure or adjacent thereto, or at some remote point. When the piston reaches a desired point in the cylinder, the motor circuit is opened and the motor stops. For example, suppose that the cylinder has 95 been entirely filled with clay and it is estimated that half of the contents should be ejected for the proper plugging of a furnace tapping hole. The motor is started and when the indicating means show that the piston 100 has reached its half-way point, the motor circuit is opened. When the time limit switch 28 is used, the motor will of course be automatically disconnected and the piston stopped at the end of its stroke before it will come into 105 harmful pressure engagement with the end of the cylinder. When the cylinder is empty and only a small quantity of clay is to be ejected, the piston can first be moved outwardly for the desired volume of clay and 110 then clay filled into the cylinder through the outer filling hole 25. If, after a complete 115 discharge of the gun, it is necessary that additional quantity of clay be ejected, the piston may be drawn inwardly a distance depending upon the additional volume desired and then clay filled in in front of the piston through the outer filling hole 25, thus avoiding the necessity of moving the piston entirely back to the inner end of its stroke. 120 Of course, when a full capacity discharge of clay is desired, clay can be filled in through both the outer and inner holes 25 and 26.

I have shown a practical and efficient embodiment of my invention but I do not desire 125 to be limited to the details disclosed as changes and modifications may be made without departing from the scope of the invention as outlined in the appended claims.

I claim as follows:

1. In a clay gun, the combination of a cylinder and a piston reciprocable therein for ejecting clay therefrom, a driving member for said piston, an indicating member moving in synchronism with said piston, and a scale providing indications corresponding with the positions of the piston within the cylinder, said indicating member traveling with the piston to indicate on the scale the positions of the piston in the cylinder.
- 10 2. In a clay gun, the combination of a cylinder, a piston reciprocable therein for ejecting clay therefrom, a screw connected with said piston and held against rotational movement, a driving nut engaging the screw and means for rotating said nut to cause axial movement of said screw and piston, a pointer on said screw, and a scale in the path of the pointer with which the pointer cooperates to indicate the position of the piston within the cylinder during operation of the gun.
- 15 3. The combination with a clay gun comprising a cylinder and a piston shiftable therein for the ejection of clay therefrom, of indicating means at a point remote from said gun for indicating the travel and the position of said piston in said cylinder.
- 20 4. The combination with a clay gun comprising a cylinder and a piston shiftable therein for ejecting clay therefrom, of electrical indicating devices and electrical circuits therefor, and switch mechanisms for said circuits operated in synchronism with the travel of the piston in the cylinder to control said circuits for indication by said indicating devices of the travel and position of the piston in the cylinder.
- 25 5. The combination with a clay gun comprising a cylinder, a piston reciprocable in said cylinder for ejection of clay therefrom, and driving means for said piston, of a series of contacts corresponding in position to the positions of the piston within the cylinder, a contact movable with the driving mechanism for the piston, electrical circuits including said contacts, and electrical indicating devices in said circuits for indicating the travel and positions of the piston in the cylinder during operation of the gun.
- 30 50 In testimony whereof I have hereunto subscribed my name at Gary, Lake County, Indiana.

AUGUST F. GIESE, JR.
